UNITED STATES PATENT OFFICE.

WALTER W. SLADE, OF BROOKLINE, MASSACHUSETTS, ASSIGNOR TO GLOBE OPTICAL COMPANY, OF BOSTON, MASSACHUSETTS, A CORPORATION OF MASSACHUSETTS.

LENS-CUTTING MACHINE.

1,388,774.

Specification of Letters Patent. Patented Aug. 23, 1921.

Application filed June 24, 1920. Serial No. 391,416.

To all whom it may concern:

Be it known that I, WALTER W. SLADE, a citizen of the United States, and resident of Brookline, in the county of Norfolk and State of Massachusetts, have invented an Improvement in Lens-Cutting Machines, of which the following description, in connection with the accompanying drawings, is a specification, like letters on the drawings representing like parts.

My present invention is an improvement in the lens cutting machine of the type shown in prior patents Nos. 813,459, issued Feb. 27, 1906, and 1,186,254, issued June 6, 1916, and the object of the invention is to improve and perfect machines of this type.

In my present improvements upon the machine of said prior patents, I have very greatly improved the general design, construction, operation and compactness, and have made the work carrying arm which is pivotally mounted and adapted to maintain the cutting tool in position to follow a pattern, with a long and rigid bearing and with the yielding means for holding the same in contact with the pattern, protected and concealed from view. Formerly the spring and its adjusting means was in the top portion of the machine and considerably in the way of the operator's view, and the adjusting chain was apt to be in the way of his work. I have now so arranged the pivotal arm and its spring and adjustment that the latter is concealed within the base of the instrument, leaving the view of the operator unobstructed and with greater freedom to operate the machine. Furthermore, this improved construction gives me the benefit of a relatively long bearing for this arm, together with a more simple casting and compact construction.

A further feature of the invention consists in the provision of means which will enable the working tool to be quickly thrown out of cutting engagement, while still maintaining all the adjustments, tension, etc., to which the apparatus has been set. This improvement is important because the adjustments for cutting must be accurately and finely made in a machine of this type and considerable time, care, skill and attention is required in the same. By my present improvement I have provided a machine which will maintain these adjustments, once made, and permit a quick and ready removal

of a completed lens and repositioning of a lens to be cut without disturbing the adjustments and by a quick and simple movement of the lever which throws the swinging arm carrying the cutting tool into or out of operative position, without changing tension of adjustments. This permits considerably increased speed in operation, saving the time required to change lenses.

A still further and very important feature of the present improvement consists in the provision of means to adjust the angular position of the cutting tool with the work. It will be appreciated that in machines of this type, where lenses for eye-glasses, or other optical devices, are being operated upon, great accuracy and delicacy of operation are necessary. Heretofore in cutting lenses the work cutting tool has been necessarily positioned in a substantially vertical plane, and therefore the angle of the cutting point, diamond or the like, has been held at a fixed angle, whereas the lenses being cut have varying arcs and consequently the cutting point has not been at right angles with the surface of the lens being cut. In high grade work it is important that the cutting point, if possible, be at right angles to the surface of the lens being cut, and my present invention is directed to obviate the difficulties heretofore experienced with a vertically positioned cutting point and to permit angular adjustment of the cutting point with relation to the surface of the lens being operated upon, whereby a substantially right-angled presentation of the point and lens can be obtained. In my present machine I provide mechanism to accomplish this result, together with the various adjustments necessary and required and also to permit such angle to be maintained during the adjustment of the work holding devices and also during the operation of the lever to swing the entire work holder out of the way of the lens to facilitate removing and positioning succeeding work, without altering the angle adjusted if desired. This angular adjustment for the cutting point is so arranged and positioned as to be quickly and readily effected at any time, in order to get the relative position of the cutting point and face or plane of the lens as nearly and accurately into right angled position as is possible.

A still further improvement consists in

the means for retaining the clamping member at one side and in permanent position out of the way of the operator, whereas formerly the spring clamping apparatus 5 was freely movable around the work holding members and this at times was apt to be in contact with the cutting point. I find that it is desirable to have the spring clamping member thus relatively fixed and accordingly have so arranged the same in the 10 present machine.

Referring to the drawings illustrating a preferred embodiment of the invention,

Figure 1 is a side view, partly in cross-section of my improved lens cutting machine;

Fig. 2 is a cross-sectional view through the base on the line 2—2 of Fig. 1;

Fig. 3 is a cross-sectional view on the 20 line 3—3 of Fig. 1; and

Fig. 4 is an enlarged end view of the angular adjusting means for the cutting point.

As shown in the drawings, I prefer to 25 build the present apparatus as a bench machine having a circular base 1 formed with a central boss 2 bored to receive a movable plunger 3, said plunger carrying a plate 4. The plunger 3 is longitudinally bored and 30 constitutes a bearing for the central stem 5 of a work table and gear wheel 10 and also for the rod 6 which extends downwardly in contact with the end of a lever 12, extending outwardly through an opening 35 13 in the walls of the base and pivoted at 14 to a pair of lugs 15, 15, as shown, the handle 18 extending at an angle preferably for convenience of the operator, whereby the lever is adapted to oscillate on its pivot 40 14 and the work table 10 raised and lowered.

Formed also at one side of the base 1 is a lug 19 and the plate 4 has a lateral extension 20 extending over said lug 19. A pin 21 projecting from the lug 19 is adapted 45 to fit within a recess 22 within the extension 20, and constitutes a guide for the plate 4 retaining the same in relative fixed position with the base and machine during the rotation of the gear wheel 10 and the raising and 50 lowering of both the plate 4 and gear 10 through oscillation of the lever 12.

In this extension 20 is formed a recess 24 adapted to receive a coiled spring 25 and normally bearing upwardly upon a lever 30, 55 which latter is pivoted at 31 to forked arms 32 extending upwardly and forwardly from the extension 20. This lever 30 is adapted to extend centrally over the work table and gear wheel 10, as indicated at 33, from 60 which a lens retaining member 35 is fitted by a ball and socket joint as indicated at 36, and carries a yielding band of rubber or the like 37 to contact with the top of the lens and hold the latter in working position 65 during the cutting operation. Mounted on

the work-table and rotatable gear wheel 10 is a coöperating rubber or yielding cushion 38 to hold the lens to be cut thus firmly and yieldingly between the cushion members 37 and 38. The lever 30 has an outwardly 70 extending portion as shown at 39, to which a latch 40 is pivoted at 41, said latch extending downwardly and adapted to engage with a tooth 42 in a recess 43 formed in said latch. Normally the spring 25 tends to 75 oscillate the lever 30 on its pivot 31 and depress the holder 35 onto the lens. Oscillation of the lever 30 by compression of the end portion 39 against the tension of the spring 25, tends to lift or raise the work 80 holding member 35 and the latch 40 will engage with the tooth 42 and thus hold the work holding member 35 upwardly during the removal of a completed lens and replacement of a succeeding lens thereon. This 85 construction is substantially shown and described in said prior patent No. 1,186,254, so far as the work holding feature is concerned and the actuation of the lever 30. In my present improvement, however, I 90 have arranged the plate 4 and extension 20 carrying the lever 30 and associated parts at one side and out of the way of the operator's work and view, retaining the same against rotative position by the arrangement of the stud 21 as above described.

Fitted to the base 1 is an upward extension 50 arranged at the rear of the base and preferably cast integral therewith. This extension 50 is cast hollow, and its upper portion is in the form of a bearing 51 to receive a shaft 52 having a gear wheel 53 keyed thereon at the uppermost portion. Said shaft extends downwardly and carries on its base and keyed thereto, a gear wheel 54, which latter projects through an opening 55 in the front portion of the hollow part 50 to mesh with the gear 10 on the rotatable work table. These gears 53 and 54 are preferably of equal diameter and of a sufficient width to permit a considerable range of vertical adjustment or movement in the work table 10 as the latter is moved upwardly in contact with the cutting point, to be described. Extending forwardly substantially over the center of the rotatable work table 10, are two brackets 56 and 57, also cast integral with the portion 50, these brackets being journaled to receive a shaft 60, which latter carries a gear 61 on its upper portion in 120 mesh with the gear 53 and preferably of the same diameter as the rotatable work holding gear 10. On the lower portion of the shaft is secured a removable pattern 62. The wheel 61 may be raised and the pattern 125 replaced by another, being slipped off the end of the shaft 60, which latter is raised out of its journal recess 64, indicated in dotted lines in Fig. 1. This construction permits a quick replacement and interchangeability 130

of patterns 62, the latter being held in non-rotatable position relatively with the shaft 60, by a pair of studs 66, 66, fitting in corresponding recesses in the pattern 62, also indicated in dotted lines in Fig. 1, and said studs being carried by a collar 67, secured to the shaft 60 by a set screw 68.

In the present machine I also cast or form a lug 70 on the side of the upright portion 50, which, in combination with a recess through the base in vertical alinement therewith, as indicated in dotted lines at 71, forms a spaced bearing for the rod 72. This rod has rigidly secured to its uppermost portion a bracket 75 provided with a pair of forwardly extending forked arms 76, 76, and constituting bearings for the work holding shaft 77. I prefer to mount the shaft 77 as a portion of a quadrant 80, having an adjustable sliding bearing 81 therein adapted to contact with the pattern 62, with a pair of spaced points to maintain the quadrant 80 and consequently the shaft 77 always at right angles, tangentially, with the pattern 62. This construction, together with the provision of a top adjustable bearing 81, indicator 82, gage 83 and adjusting nut 85 for the removal bearing or slide 81, is substantially identical with the construction shown and described in said prior patent 813,459, and therefore will not be further described here in detail.

My present improvement provides an adjustable means to carry the diamond cutting point 90 on its holder 91 so as to permit angular adjustment thereof with regard to the face of the lens being operated upon while utilizing to the fullest advantage the construction of indicator, sliding bearing, etc., and the features of said prior patents. To this end I attach to the shaft 77 a block 100, having therein an undercut groove 101 in the form of an arc, said block being rigidly secured to the shaft 77 by a set screw 103, the block 100 being bored to receive the projecting end portion of the shaft 77.

Fitted to oscillate in the arced groove 101 is the dovetailed portion 105 of an adjustable member 106, the latter carrying rigidly therewith a cutter or diamond holder 91. Consequently the lateral adjustment of the member 106 with its groove 105 in the recess 101 and the block 100, permits angular adjustment of the cutting point 90 through a considerable range, permitting said point to be adjusted and positioned with great nicety and exactness against the varying curves of different lenses to be cut, and allowing a substantially complete and perfect right angled contact of said cutting point with the lenses, as will be readily understood.

In order to hold the adjustable member 106 in adjusted position I may provide a set screw 110 threaded through the member 106

and adapted to contact with the bottom of the groove 101 and the fixed block 100. However, as usually only two or three different angular positions are desired in ordinary work, I prefer to have these angular positions predetermined and automatically locked therein by a simple manual movement of the member 106. For this purpose I form in the topmost surface of the grooved part 105, a series of holes 112, adapted to receive the rounded end of a plunger 115, which plunger extends through a corresponding recess in the fixed block 100 and is secured to the end of a spring 120, the latter attached by a bolt 121, in the side of the block. Consequently with the set screw 110 released or not sent home, the block 106 can be instantly and manually shifted from one position, where the plunger 115 engages a hole 112 to the next, springing out the rounded end of the plunger as the block is moved and automatically locking the same when the plunger engages the desired recess 112. This affords a quick and locked adjustment, the set screw 110 permitting adjustment intermediate the lock points.

In order to still further facilitate the ready removal and replacing of the adjusted cutter arm and assembled parts, I provide the entire bracket mounted on said post 72 with adjustable yielding means to hold the bracket and sliding guide 81 in contact with the pattern 62 and yet to quickly remove the same out of contact with the work 100 while all parts are in adjusted position. In carrying out this feature of the invention I extend from the bottom of the rod 72, within the base 1 of the machine, an arm 130 (see Fig. 2), to which is attached one end of a coiled spring 133 having its other end secured to a chain 134 which is led through a hole 135 in the base and across a slotted locking plate 136, which latter is adapted to receive any predetermined link of the chain 134 and thus hold the spring 133 under desired tension and consequently to hold the block 81 in adjusted and tensioned contact with the pattern 62. The bracket 75 has on its inner faces contact plate 140 adapted to bear upon the face 141 or 142 of a lever 144, the latter pivoted at 146 to the inner face of the upright 50 and having its outer or handle end 150 extending outwardly. The pivot 146 is so positioned with regard to the bearing plate 140 and the faces 141 and 142 that when the lever 144 is swung downwardly through the application of pressure on the handle 150 and the face 142 brought in contact with the plate 140 forcing the entire bracket 75 to swing on its pivot post 77 and against the action of the spring 133, the bracket will be automatically held in this downwardly swinging position, thus simultaneously removing the 130

cutter 90 and its holder 91 from immediate contact and position against the lens or from its normal cutting position if the lens has been lowered.

5 The operation of my present improved machine is substantially similar to that of said prior lens cutting machines. A lens being positioned upon the rubber support 38, the clamping lever 33 is released and the 10 yielding portion 37 brought in contact with the top of the lens, and held in this position through the action of the spring 25. The angular adjustment for the cutting point 90 having been effected through sliding movement of the member 106 in the block 100, the operator then depresses the handle 18, thus raising the plate 4, gear wheel 10, and the lens thus in clamped position thereon, against the cutting point 90, 15 the operator simultaneously actuating the handle 155 on the gear wheel 60 to rotate the same. It will be understood that a desired and suitable pattern 62 has been positioned and that the cutter will, of course, 20 follow the contour of said pattern 62. The operator rotating the wheel 61 and consequently the work table gear 10 and applying desired pressure through the handle 18 for the cutting operation, the lens cutting 25 operation is performed, the handle 18 released and the lever 144 depressed to move the work and bracket 77 away. The lever 30 is oscillated to release the lens and the latch 40 will raise the lever 30 in position, 30 or the operator can thus hold the same, whereupon the clamp is lowered into lens engaging position, the lever 144 snapped upwardly, and the cutter and bracket brought back into original adjusted position 35

for immediate performance of the succeeding cutting operation. Various adjustments can, of course, be made from time to time in my present machine and for all purposes, as explained in said prior cases.

My invention is further described and defined in the form of claims as follows:

1. A lens cutting machine of the kind described, comprising a swinging support for said cutter, adapted to be held under spring tension toward the work to be operated on, 50 and a lever operable to move the work holder out of operative position.

2. A lens cutting machine of the kind described, comprising a work holder, having a cutter, means to secure angular adjustment 55 between the cutter and the holder, said holder being pivotally mounted to be swung out of operative position, and a pivoted cam lever, operable to swing the work holder while having its cutter in adjusted position, 60 out of operative position.

3. A lens cutting machine of the kind described, comprising a work holder, having a cutter, means to secure angular adjustment 65 between the cutter and the holder, said holder being pivotally mounted to be swung into or out of operative position, and a pivoted cam lever, operable to swing the work holder while having its cutter in adjusted position, 70 out of operative position, said lever having a two-faced bearing surface in contact with the support and in a position relatively with its pivot to hold the support locked in outward position.

In testimony whereof, I have signed my 75 name to this specification.

WALTER W. SLADE.
